PLAY PIPE CONSTRUCTION

Wayne B. Thompson, Winchester, Mass., assignor
to Spray Engineering Company, Somerville,
Mass., a corporation of Massachusetts

Application August 28, 1937, Serial No. 161,460

9 Claims. (Cl. 299—112)

The present invention relates to apparatus for use in extinguishing fires. More particularly, the present invention relates to apparatus for use in extinguishing fires on the surface of inflammable liquids, such as oil, which are immiscible with water.

Such fires present an extinguishing problem not found in the case of burning non-liquid materials. Whereas with the latter the application of more or less solid streams of water is effective, in the case of oil fires such streams are not effective and serve chiefly to spread the fire. But while such application of water is not effective to extinguish an oil fire, it by no means follows that an oil fire can not be extinguished by the use of water. The explanation lies in the manner in which the water is applied, and considerable success has been attained in extinguishing oil fires by directing upon them a spray of highly atomized or finely divided water particles, something quite different from a solid stream or jet of water. The principle of extinguishing by this method is that the flames turn the water into steam, this being effected very quickly because the heat acts on minute water particles, and then the steam acts as a blanket over the fire, putting it out by excluding the air necessary to support combustion. In the performance of this process the surface of the oil is not disturbed by the spray, and thus there is none of that spattering or splashing or churning of the burning oil which, as is well known, serves to scatter and spread it.

Because of the nature of an oil fire, stationary spray-forming apparatus is not suitable to use. The flames must be chased, as it were, as they recede over the surface of the oil, thereby rendering ineffective apparatus mounted to discharge at only a given area. For the same reason apparatus mounted for movement is not satisfactory either, for the great pressure of the water at the nozzle (around 100 pounds or more per square inch) results in great resistance to movement of the apparatus, and quite independently of any pressure resistance, the field of play is at best limited, a situation that should not exist when it comes to extinguishing a burning substance that may flow freely.

As a consequence it is the practice to use water spray apparatus of the manually operated type, and because of the great water pressure necessary for an effective spray, the apparatus is commonly handled by two men at the nozzle or discharge end. It should also be pointed out that the discharge end of the apparatus does not comprise merely an elongated nozzle coupled to a hose, but

comprises a nozzle mounted on one end of a pipe, called a play pipe, the other end of which is coupled to the hose. The axis of discharge from the nozzle is a continuation of the longitudinal axis of the play pipe, and the hose coupling may or may not have associated therewith handles which aid the men in dragging the hose along the ground and in supporting the pipe, their other hands grasping the pipe forwardly from its base. Play pipe constructions differ from standard fire nozzles in that the latter are used from a distance, the long carry of the emitting solid stream taking a more or less arcuate course, while the former, lacking that carry for the spray, are necessarily used rather close up, the wide spread of the spray forming a shield which protects the men from the heat.

But while play pipe constructions are improvements over stationary and movably mounted nozzles, they still exhibit the difficulty of being unwieldy and awkward to handle and are not adapted for quick or abrupt changes in the direction of the spray to effect the ready and continuous flame chasing necessary for the most efficient and rapid operation. They likewise are unsuited for directing a spray downwardly over the edge of a tank, or around obstacles such as machinery in a ship engine room, for one example. The weight and length of the play pipe construction are factors in this, of course, but the real cause of the difficulty of such manipulation lies in the fact that the constructions are not adapted to counteract and offset the tendency which the great pressure of the rushing water has to make the nozzle and adjacent hose portion assume the straight line or axial direction of the water rushing from the main body of the hose and to resist any effort to change the direction of the discharge so that the spray can be played on different surface areas.

It is the principal object of the present invention to obviate this difficulty, that is, to provide a spray-forming play pipe construction which may be handled with ease and speed to cause the spray to take any desired direction, as is necessary for the most rapid extinguishing of fire on the surface of a body or pool of oil.

To the accomplishment of this object and such others as may hereinafter appear, the present invention resides in certain devices, constructions, and combinations of parts, all fully described in the following specifications and then pointed out in the appended claims, possessing advantages and merits which will be appreciated by those skilled in the art.

The various features of the present invention will be readily understood from inspection of the accompanying drawing, illustrating the best embodiment of the present invention now known to 5 the inventor, in which

Figure 1 is a view of the apparatus in front elevation;

Fig. 2 is a view in left side elevation;

Fig. 3 is a view in plan;

10 Fig. 4 is a detail view in sectional elevation taken along the line 4-4 of Fig. 2;

Fig. 5 is a detail view in sectional elevation, similar to Fig. 4, but showing a modification of the piping and coupling;

15 Fig. 6 is a detail view in sectional elevation taken along the line 6-6 of Fig. 2; and

Fig. 7 is a view in sectional elevation of the nozzle.

Referring to the drawing, the construction is 20 provided with a hose coupling member 10 (Figs. 1, 2, and 6) which is interiorly threaded at 11 to receive a male coupling member (not shown) attached to a nose, as is well understood. The coupling member 10 is provided with a lower reduced cylindrical portion 12 terminating downwardly at a transverse shoulder 13 which serves as a rest or stop for a ring 14. At opposite sides the ring is provided with outwardly extending, generally U-shaped handles 15 adapted to be 25 grasped when the apparatus is in use. The ring 14 is held on the coupling member 10 by a sleeve 16 the lower portion of which is threaded on the upper reduced portion 17 of the coupling and extends outwardly over the ring, as indicated. 30 The reduced portion 17 has a smaller diameter than the reduced portion 12, thereby resulting in the formation of a shoulder 18 which serves as an abutment for the bottom of the sleeve 16. The internal diameter of the ring 14 is appreciably 35 greater than the external diameter of the reduced portion 12, and as indicated in Fig. 6 the height of the ring is slightly less than that of the reduced portion 12. With this construction the ring is free to be rotated on the coupling member 40 45 10, but the abutments or stops provided by the shoulder 13 and the bottom of the sleeve 16 effectively maintain the ring mounted on the coupling. The sleeve is preferably locked against rotation on the coupling member, as by one or more set screws 19, thereby making the members 10 and 16 an operative coupling unit.

Threaded into the sleeve 16 is one end of a length of pipe 20, the other end of which is threaded into the lower portion of a coupling 21. 50 The upper portion of the coupling 21 receives the threaded lower end of a second and longer length of pipe 22, preferably of the same diameter as the length 20 and axially aligned therewith so as to make an effective extension thereof. In 55 order to make the connections between the sleeve 16 and the pipe 20, and between the coupling 21 and the pipes 20 and 22, strong and to provide for support against any tendency of the piping to warp or bend at the sleeve and the coupling 21 as the apparatus is moved during use in opposition to the force of the rushing water, the sleeve is provided with an integral, internally cylindrical extension 23 (Fig. 6) which embraces the end portion of the pipe 20, and the coupling is provided with similar integral, internally cylindrical extensions 24 and 25 (Fig. 4) which embrace the adjacent end portions of the pipes 20 and 22, respectively. While the construction as thus described is sturdy, its strength, particularly against 60 any turning of the pipe ends in the sleeve 16 and

the coupling 21 may be augmented by brazing the sleeve to the pipe 20 as indicated at 26 and by brazing the coupling 21 to the pipes 20 and 22, as indicated at 27 and 28, respectively. This construction, together with the set screws 19, makes 5 for a coupling, sleeve, and piping arrangement that is operatively integral and fixed against relative movement among its parts.

In order to effect the desired discharge of water from the apparatus, the upper end of the 10 pipe 22 is provided with a nozzle 29 of the type adapted to discharge a bushy and full or homogeneous cone of spray comprising water in a highly atomized or finely divided state—this in contrast to the more or less solid stream or jet 15 emitting from standard fire nozzles. While any nozzle may be used which is capable of producing the desired spray, it is much preferred that the nozzle have the general structure and mode of operation of that disclosed in the patent to 20 Aubrey G. Eneas, No. 1,101,264, as this nozzle has been found to be highly effective in the use of the illustrated embodiment of the present invention to produce the type of spray desired for extinguishing oil fires. While the details of construction and operation of the Eneas nozzle may be ascertained from the above-noted patent, it may be said, with reference to Fig. 7, that the nozzle comprises a shell or casing 30 within which is mounted a water guiding member 31 provided 30 with vanes 32 which give a swirl to water entering the nozzle and effect the production of swirling streams 33 within a mixing chamber 34. The member 31 is also provided with a central axial passage 35 providing for a central jet of water 36 35 which mixes with the swirling streams 33 within the mixing chamber. By reason of this construction, water entering the nozzle is discharged as a full cone spray of highly divided or atomized particles.

For reasons which will be explained below, the axis of discharge from the nozzle 29 is angularly disposed to the longitudinal axis of the piping 20-22. This is effected by giving the upper portion of the pipe 22 a 45° bend 37 (Figs. 2 and 3), 45 although it will be appreciated that the same result can be obtained by providing the base of the nozzle with the bend and by leaving the pipe 22 entirely straight.

The construction is completed by the provision 50 of a second set of handles mounted on the piping. To this end, and referring to Figs. 1-4, the coupling 21 is provided laterally with oppositely disposed bosses 38 into each of which is threaded one end of a handle 39 so as to always have the 55 same position with respect to the coupling, in contrast to the movability of the handles 15. The handles 39 extend outwardly from the coupling 21 and the piping 20-22, preferably being normal to a plane passing through the axis of the piping 60 and the discharge axis of the nozzle 29. The handles 39 may be rods as shown, or they may have an equivalent operative construction, and they may be provided with rotatable grips or covers, but the important point is that so far as 65 the operation and handling of the apparatus during spray discharge are concerned, the connection of the handles proper with the coupling 21 should not be a swinging one, so that the handles are not movable or swingable toward or circumferentially of the coupling and the piping during 70 spray discharge but remain outstanding. The handles have sufficient length so that when grasped the hand is well spaced from the piping, and the mounting of the handles in the bosses 38 75

may if desired be fixed in threaded-in position by means of brazing 40.

In the construction described above the piping has been illustrated as being in two portions, 20 and 22, with the coupling 21 serving to connect them in axial alignment and also serving to join the handles 39 to the piping. An alternative construction in this respect is shown in Fig. 5, characterized by the fact that instead of employing two pipe portions, as 20 and 22, only a single length 41 of pipe is used, having the overall length of the piping 20-22 as joined by the coupling 21, and being connected at its lower end to the hose coupling member 10 and supporting the nozzle 29 at its upper end all in the same manner as shown in Figs. 1, 2, and 3.

In order to mount the handles 39 on the piping 41, a support such as a collar 42 is provided which has a smooth cylindrical interior adapted to embrace the piping 41 and which is maintained fixed in its embracement therewith by means of brazing 43 at its opposite ends. To receive the threaded ends of the handles 39, the coupling 42 is provided laterally with oppositely disposed bosses 44, and the handles may if desired be maintained in the bosses 44 by means of brazing 45. As is the case with the coupling 21 as shown in Figs. 1 and 2, the collar 42 is spaced from both the handles 15 and the nozzle 29, being nearer to the former.

In using either of the illustrated embodiments of the present invention, the coupling member 10 is connected to a suitable hose construction as is well understood. Preferably two men support and operate the apparatus, one hand of each man grasping a handle 15 and their other hands grasping the end portions of the handles 39, respectively. As this provides for a firm gripping of the apparatus since the handles 39 do not swing, it will be seen that the hose may with minimum difficulty be dragged along the ground toward the fire or otherwise moved as occasion requires. By reason of the piping 22 or 41 extending forwardly of the handles 39, the nozzle may be located in close proximity to the fire while the men stand away out of its immediate heat, and further heat protection is afforded by the bushy cone spray which acts as a shield and as is well known is cool because of its atomization. By reason of the bend 37 the apparatus need not be held so that the piping 20-22 or 41 is pointed directly at the fire area being sprayed, which would generally be downward as in the case of a burning pool or burning oil on a floor—this manner of holding and the ease which it involves being in direct contrast to the position necessary for piping where the direction of the discharged spray is axial of the piping. Since the grasping of the handles 39 affords a better hold and a relatively great movement leverage in contrast to gripping the piping itself, the apparatus may be conveniently moved, and the adjacent hose portion moved also, to cause the discharge to take different directions as the steam blanket produced over one sprayed area causes the flames to recede to a different area. Also by reason of this better gripping and leverage the movement of the apparatus may be speedy, which is much desired and is in contrast to the use of present apparatus, for the leverage resulting from gripping the handles 39 is much more effective than that from merely gripping the piping itself to overcome the resistance to movement occasioned by the high pressure rushing water in the piping and the hose.

It will be further apparent, by reason of the bend

31 together with the movement facility arising from gripping the handles 39, that the spray can be directed downwardly over the edge of a tank against flames immediately adjacent its walls, a mode of operation impossible with play pipe constructions in which the direction of spray discharge is axial of the piping. By the same token, the apparatus can get around obstacles other than tank sides, such as around machinery or between parts thereof, for example, in a much easier manner than is the case with the straight type of construction mentioned above, and as a matter of fact, the present invention may be used to get at parts or places which a straight construction can not reach at all. The high efficiency of the illustrated embodiment of the present invention will thus be readily appreciated.

But while the remarks in the preceding paragraph have been concerned with a general description of the operation and effectiveness of 20 the present invention, there is a further operative point of great importance, not brought out above and impossible with present apparatus.

In using present play pipe constructions, i. e., 25 constructions in which the direction of spray discharge is axial of the piping, the spray can be played about or over different surface areas only by swinging the piping bodily from side to side or up or down, the hose coupling portion being roughly the pivot area for these movements, or 30 by moving the entire apparatus bodily from one location to another. The high pressure water rushing through the piping and the hose results in considerable resistance to these movements, but as is well known this resistance can be overcome and the apparatus moved, and such overcoming is accomplished with the pipe itself being gripped by the hands that are not holding onto the base of the piping or handles thereof. However, that leverage which is sufficient to effect 35 such movements, i. e., which arises from the gripping of the pipe itself, is quite insufficient to enable the men to rotate the piping on its longitudinal axis, and thus this type of piping movement, in contrast to those mentioned above, is 40 quite out of the question. There is also involved, in addition to the rotary movement of the piping, a rotary movement of at least the adjacent hose portion, and with the type of hose necessary to accommodate the high water pressure and to provide a sufficient volume of water, together with the nature of the piping, such rotary movement is not possible by a mere gripping 45 of the piping manually.

I am well aware, however, that the occasion for 50 this rotary movement never arises with present play pipe constructions because with a direction of spray discharge that is axial of the piping, that discharge direction will always be the same no matter what the rotative position of the piping may be. But this very sameness of direction brings out by contrast a highly important point in the use of the present invention, in that my improved construction is such that there can actually be accomplished that rotary movement 55 of the piping which is out of the question where the piping itself is gripped and at the same time that rotary movement is accompanied by a change in the direction of discharge—this in contrast to the sameness of direction which would result 60 with present constructions if a gripping of the piping itself could accomplish rotative movement of the piping and the adjacent hose portion.

The gripping of the handles 39 at points spaced from the piping 20-22 or 41 supplies, for rota- 75

tively moving the piping, the very leverage which mere pipe gripping precludes. Since the coupling member 10 is free to rotate within the ring 14, as a sort of guide, the handles 39 may be used 5 to rotate the piping about its longitudinal axis, thereby effecting a change in the direction of the nozzle discharge because rotative movement of the piping causes the nozzle 29 to swing about the bend 37 as a pivot. Moreover, in contrast to the 10 bodily movement and change of position of the workmen themselves which must take place in using present constructions to effect a spray direction change that is even as little, as is represented by a 90° swing, for example, of the nozzle 15 29, in using the present invention such a change of spray direction may be accomplished without the taking of a step by the men and with no more movement on their part than is necessary to turn the piping by means of the handles 39. 20 As this mode of operation provides sufficient turning leverage, it will be seen not only that the present invention can be used in a manner impossible with present constructions but also that a highly desirable speed and fineness of 25 movement is accomplished in contrast to the slow and awkward movements which are necessitated when the piping can not be rotated manually or the direction of discharge is axial of the piping. The speed and effectiveness of turning 30 the piping so as to chase the flames is not confined to spraying generally over the body of oil, but is also present when spraying over tank sides and around or between other obstacles. In fact, in these latter examples the turning of the piping 35 to swing the nozzle is particularly useful and advantageous over present constructions since the necessary changes in spray direction will frequently be small.

It will be seen that various changes may be 40 made in the illustrated embodiments of the present invention without departing from the true scope of the actual invention set forth in the claims herewith. The particulars illustrated and described are not, therefore, to be considered 45 essential. While the present invention has been disclosed in connection with the extinguishing of oil fires, it will be seen that it is not limited to this use, and it is contemplated that the apparatus may be constructed for manipulation 50 by one man instead of two, although the latter is preferred. While the dimensions of the various parts of the embodiment shown may obviously be varied as desired to suit a given situation, it may be stated that in one embodiment 55 that has been successfully used in extinguishing oil fires, the over-all length, from the base of the coupling member 10 to the tip of the nozzle 29, is approximately six feet, the distance from the axis of the handles 39 to the base of the coupling member 10 is approximately 33 inches, and the handles 39 measure approximately 15 inches outwardly from the center of the piping. With a water pressure of 100 pounds or more a hose diameter of 2½ inches is commonly used, and 60 the coupling member 10 therefore has an internal diameter such as to receive a coupling proper for such hose.

What is claimed as new is:

1. A play pipe construction having, in combination, a hose coupling member, piping fixedly connected at one end to the coupling member so as to be stationary throughout relatively thereto, a nozzle for discharging an atomized spray mounted on the other end of the piping so that 65 the axis of spray discharge is angularly disposed 70

to the longitudinal axis of the piping, a handle construction rotatably associated with the coupling member, and means connected to the piping for facilitating its manipulation and for turning it on its said axis to vary the direction of the 5 spray discharge.

2. A play pipe construction having, in combination, a hose coupling member, piping connected at one end to the coupling member so as to be stationary throughout relatively thereto, a nozzle for discharging an atomized spray mounted on the other end of the piping so that the axis of spray discharge is angularly disposed to the longitudinal axis of the piping, a handle construction rotatably associated with the coupling member, and means connected to the piping and spaced from said handle construction for facilitating the manipulation of the piping and for turning it on its said axis to vary the direction of the spray discharge. 20

3. A play pipe construction having, in combination, a hose coupling member, piping fixedly connected at one end to the coupling member so as to be stationary throughout relatively thereto, a nozzle for discharging an atomized spray 25 mounted on the other end of the piping so that the axis of spray discharge is angularly disposed to the longitudinal axis of the piping, a handle construction rotatably associated with the coupling member, and means connected to the piping and spaced from both said handle construction and the nozzle for facilitating the manipulation of the piping and for turning it on its said axis to vary the direction of the spray discharge. 30

4. A play pipe construction having, in combination, a hose coupling member, piping fixedly connected at one end to the coupling member so as to be stationary throughout relatively thereto, a nozzle for discharging an atomized spray 35 mounted on the other end of the piping so that the axis of spray discharge is angularly disposed to the longitudinal axis of the piping, a handle construction rotatably associated with the coupling member, and another handle construction non-swingably mounted on the piping. 45

5. A play pipe construction having, in combination, a hose coupling member, piping fixedly connected at one end to the coupling member so as to be stationary throughout relatively thereto, a nozzle for discharging an atomized spray 50 mounted on the other end of the piping so that the axis of spray discharge is angularly disposed to the longitudinal axis of the piping, a handle construction rotatably associated with the coupling member, and another handle construction non-swingably mounted on the piping and spaced from both the first handle construction 55 and the nozzle.

6. A play pipe construction having, in combination, a hose coupling member, piping fixedly 60 connected at one end to the hose coupling member so as to be stationary throughout relatively thereto, a nozzle for discharging an atomized spray mounted on the other end of the piping so that the axis of spray discharge is angularly disposed to the longitudinal axis of the piping, a handle construction rotatably associated with the hose coupling member, a coupling fixed to the piping, and a handle construction non-swingably mounted on said piping coupling. 65

7. A play pipe construction having, in combination, a hose coupling member, piping fixedly connected at one end to the hose coupling member so as to be stationary throughout relatively thereto, a nozzle for discharging an atomized 70 spray 75

- 5 spray mounted on the other end of the piping so that the axis of spray discharge is angularly disposed to the longitudinal axis of the piping, a handle construction rotatably associated with the hose coupling member, a coupling fixed to the piping and spaced from both the first handle construction and the nozzle, and another handle construction non-swingably mounted on said piping coupling.
- 10 8. A play pipe construction having, in combination, a hose coupling member, a pipe fixedly connected at one end to the hose coupling member, a pipe coupling mounted on the other end of the pipe, a second pipe fixedly connected to said pipe coupling so as to form therewith an operative extension of said first pipe, a nozzle for discharging an atomized spray mounted on the other end of the second pipe so that the axis of spray discharge is angularly disposed to the longitudinal axis of at least the second pipe, a handle construction rotatably associated with the first coupling member, and another handle construction non-swingably mounted on the pipe coupling.
- 15 9. A play pipe construction having, in combination, a hose coupling member, a single length of pipe fixedly connected at one end to the hose coupling member, a nozzle for discharging an atomized spray mounted on the other end of the pipe so that the axis of spray discharge is angularly disposed to the longitudinal axis of the pipe, a handle construction rotatably associated with the hose coupling member, a support embracing the pipe length and fixed thereon between the hose coupling member and the nozzle, and a second handle construction non-swingably mounted on the support.

WAYNE B. THOMPSON.

CERTIFICATE OF CORRECTION.

Patent No. 2,134,347.

October 25, 1938.

WAYNE B. THOMPSON.

It is hereby certified that error appears in the printed specification of the above numbered patent requiring correction as follows: Page 2, first column, line 23, for "nose" read hose; page 4, second column, line 8, claim 2, before the syllable "connect-" insert fixedly; page 5, second column, line 3, claim 8, for "first" read hose; and that the said Letters Patent should be read with this correction therein that the same may conform to the record of the case in the Patent Office.

Signed and sealed this 6th day of December, A. D. 1938.

Henry Van Arsdale
